UNITED STATES PATENT OFFICE.

WILLIAM D. BALDWIN, OF NEW YORK, AND AUGUST SUNDH, OF YONKERS, NEW YORK, ASSIGNORS TO OTIS ELEVATOR COMPANY, OF EAST ORANGE, NEW JERSEY, A CORPORATION OF NEW JERSEY.

SHIFTING DEVICE FOR PIERS, &c.

SPECIFICATION forming part of Letters Patent No. 700,599, dated May 20, 1902.

Application filed December 17, 1901. Serial No. 86,333. (No model.)

To all whom it may concern:

Be it known that we, WILLIAM D. BALDWIN, residing in the city and county of New York, and AUGUST SUNDH, residing at Yonkers, in the county of Westchester, State of New York, citizens of the United States, have invented certain new and useful Improvements in Shifting Devices for Piers, &c., of which the following is a specification.

10 Our invention relates to that class of hoists or devices wherein a capstan is arranged above a footway, with operating means arranged in a vault beneath, so that a cable may be readily applied to and carried from 15 the capstan for hauling, lifting, and other purposes; and our invention consists of means whereby the movements of the said capstan may be derived from a motor turned in one direction, as fully set forth hereinafter and 20 as illustrated in the accompanying drawings, in which—

Figure 1 is a sectional elevation showing part of a footway, vault, capstan, and operating appliances embodying our invention.

25 Fig. 2 is a sectional plan below the cap or roof of the vault. Fig. 3 is an elevation showing a modification wherein the driving-pulleys operate upon the driving-disk through the medium of gears, and Fig. 4 is a part sectional plan of the construction shown in Fig. 3 upon a plane directly below the footway.

Below the platform, which may be the footway of a pier or embankment A, is a vault X, within a casing in which is a motor M for 35 imparting movement at different speeds and in different directions to a shaft 7, extending through the cap or cover 9 of the casing, and at the outer end of the shaft is secured a capstan B. The motor M is illustrated as an 40 electric motor having a switch-casing D, in which the switch is connected to a shaft 1, geared with a vertical shaft 20, extending upward into a socket in the cap 9 and provided with a rectangular head on which to apply a 45 key 21 for turning the switch-shaft and stopping and starting the motor or increasing or decreasing its speed. This action of the elements contained within the switch-casing is so well known as not to require any illustration of the devices used for securing these re-

sults. The motor-shaft 3 in this case rotates only in one direction and carries two driving-pulleys 30 31, which are connected with the shaft by means of a feather 32, so as to turn therewith but slide thereon, whereby either 55 driving-pulley may be brought into action to drive a disk 33, secured to the shaft 7. As shown in Figs. 1 and 2, the driving-pulleys are cone-pulleys engaging directly the cone-like surface of the disk 33. In the construction shown in Figs. 3 and 4 the driving-pulleys 30 and 31 engage conical sockets in the hubs of spur-wheels 35 36, each of which 60 gears with an annular gear upon the disk 33. In either case when one driving-pulley, 30, is 65 brought into frictional engagement with its coacting part it serves to drive the disk 33 in one direction, and when the other driving-pulley, 31, is brought into engagement with its coacting part it drives disk 33 in the opposite direction, while by placing both driving-pulleys in an intermediate position and out of contact with the coacting parts the disk 33 is not acted upon and will remain at rest. 70

Different means may be employed for shifting the position of the driving-pulleys. In the construction shown in Figs. 1 and 2 the driving-pulleys are connected by an intermediate sleeve 37, having an annular groove 38 for receiving pins upon the opposite side of a 80 forked lever 39, connected to a shaft 40, from which an arm 41 extends to one side and is connected by a link 42 with a lever 43, pivoted to a hanger 44, suspended from the cap 9. Two rods 45 46 extend upward through the 85 cap 9 in such position that the operator, who occupies a position adjacent to the handle or key 21, may place his foot upon either rod 45 or 46, and thereby shift the position of the driving-pulleys. There is a like arrangement 90 in the construction shown in Figs. 3 and 4.

It is necessary, as the parts are heavy and acquire considerable momentum when driven at a high speed, to apply a brake as the driving-pulleys are brought to the intermediate 95 position, this further being required in order that the capstan may remain stationary when heavy loads are suspended from the cable wound thereon. We therefore make use of a strap-brake K, the strap 49 of which passes 100

around a hand-wheel 50 on the shaft 7 and is connected at opposite ends to arms upon a shaft 51, supported by a pendent bracket 52. A third arm 53 upon the shaft 51 extends 5 through an opening in a slide 54, carrying set-screws 55 56, which bear upon the arms 57 58 of a T-head lever 59, pivoted to a pendent bracket 60 and connected by a link to the lever 43, so that when either of the rods 45 10 46 is depressed the lever 59 will be rocked and will thereby push back the slide 54 and turn the shaft 51 in the direction of its arrow, Fig. 2, to thereby relax the draft upon the brake-strap. Normally, however, the slide 15 54 is carried in the reverse direction by the action of a heavy weight 61 upon one arm of a bell-crank lever 62, pivoted to a bracket 63 below the cap 9, so that the brake will be applied except when one of the rods 45 46 is depressed and as long as it is depressed during 20 the action of the apparatus. A somewhat similar construction is shown in Figs. 3 and 4, where the parts are somewhat differently proportioned and arranged to effect the same 25 result.

We do not herein claim, broadly, the combination of a capstan and its operating means with the footway of a pier or embankment, the same being set forth in our application, 30 Serial No. 86,332, filed December 17, 1901.

Without limiting ourselves to the precise details of construction and arrangement of parts shown, we claim as our invention—

1. The combination with a capstan arranged 35 above the footway of a pier or embankment, and with a shaft extending downward into a vault below the footway, of a motor adapted to rotate in one direction, a pair of driving-pulleys upon the shaft of the motor, a driv-

ing-disk carried by the shaft of the capstan, 40 means for shifting the pulleys to bring one or the other into engagement with the disk, and control devices for regulating the speed and stopping and starting the motor and for shifting the pulleys, substantially as set forth. 45

2. The combination with the footway of a pier or embankment, of a capstan arranged above the same, a shaft extending through the footway to a vault below the same and provided with a driving-disk, a motor adapted 50 to rotate in one direction, driving-pulleys driven therefrom and adapted to be shifted alternately into and out of engagement to drive the said disk, a control device for stopping and starting and regulating the speed 55 of the motor having an operating device above the footway, a brake device, means extending above the footway for shifting the driving-pulleys, and connections between said means and the brake device, substantially as 60 set forth.

3. The combination with the footway of a pier or embankment, of a capstan, driving-disk, motor, pulleys driven from the motor and adapted to be alternately brought into 65 action to drive the disk in opposite directions, means for shifting the pulleys extending to the footway, a brake device, and connections between the brake device and the means for shifting the pulleys, substantially as set forth. 70

In testimony whereof we have signed our names to this specification in the presence of two subscribing witnesses.

WILLIAM D. BALDWIN.
AUGUST SUNDH.
